UNITED STATES PATENT OFFICE

WILLIAM O. ROEDER, OF OSHKOSH, WISCONSIN

TOY

Application filed April 18, 1931. Serial No. 531,182.

This invention relates to toys and has for the primary object, the provision of a device of the above stated character which will provide amusement to both children and adults and will represent a hurdle race between two or more figures which may be in the form of horses ridden by jockeys or may be in any other form of animal.

Another object of this invention is the provision of a track having a hurdle and over which the figures are propelled by a driving means and in such a manner that the figures will have a galloping effect and will elevate the figures when arriving at the hurdle so that they clear the latter with the effect of a closely contested race.

A further object of this invention is the provision of means whereby the figures during their travel about the track will have the effect of gaining and losing in the race relative to each other.

A still further object of this invention is the provision of a toy of the abovestated character which will be simple, durable and efficient and which may be manufactured and sold at a comparatively low cost.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a top plan view illustrating a toy constructed in accordance with my invention.

Figure 2 is a side elevation illustrating the same.

Figure 3 is a bottom plan view illustrating the power source.

Figure 4 is a side elevation partly broken away illustrating the power source and the figures in the act of passing over the hurdle.

Figure 5 is a detail sectional view illustrating an operating means between the power source and the figures.

Figure 6 is a side elevation illustrating one of the figures.

Figure 7 is a detail view partly in section illustrating a modified form of means for mounting the figures.

Figure 8 is a side elevation illustrating a modified form of figure.

Figure 9 is a perspective view illustrating a clip for preventing side motion of the figures during the operation of the device.

Referring in detail to the drawings the numeral 1 indicates a circular base, the top face of which forms an annular track 2 having mounted thereon a hurdle 3. The base 1 centrally of the track is provided with a socket or depression 4 having an aperture to receive the lower end of a vertically disposed post 5 carrying at its upper end a segmental gear 6. The gear and post remain stationary and said post has journalled thereon a sleeve 7 to which a gear 8 is secured and located within the depression 4 and extending through a slot 9 formed in one wall thereof to mesh with a train of gears forming a part of a spring motor 10 mounted within the base. The sleeve 7 is held against upward movement on the post by a stop collar 7.

It is to be understood that the base is of hollow formation so that the motor may be located therein as clearly shown in Figure 4 and has a control 11 which extends through a slot 12' in the track 2 whereby the motor may be set in operation and stopped when desired.

An upwardly and outwardly diverging arm 12 is secured to the sleeve 7 and rotates therewith and carries at the outer end a journal 13 to rotatably support a shaft 14 which has secured at its inner end a gear 15 engaging the teeth of the segmental gear 6, whereby upon the movement of the shaft in a circular path about the track by the rotation of the

sleeve 7, the shaft 14 will be rotated. The outer end of the shaft is formed into a pair of cranks 16 on which are pivotally mounted figures 17. Spacing collars 18 are located on the cranks 16 at opposite sides of the figures 17 for the purpose of preventing the figures from having undue side motion consequently preventing the figures from becoming tangled with each other during the operation of the device.

The journal 13 is pivotally secured to the outer end of the arm 12 as shown at 19 and a tension spring 20 is interposed between the journal and the arm by being mounted on the pivot 19 for the purpose of normally urging the inner end of the shaft downwardly thus maintaining the gear 15 in mesh with the segmental gear 6. The segmental gear 6 has formed thereon a downwardly inclined lip or flange 21 adapted to be engaged by the gear 15 during the travel of the shaft 14 about the track, and as the gear leaves the segmental gear 6 and moves downwardly by the action of the spring 20 the outer end of the shaft is elevated. The elevating of the outer end of the shaft takes place when the figures arrive adjacent to the hurdle and after the figures have passed the hurdle, the gear engages the lip elevating the inner end of the shaft and lowering the outer end thereof to bring the figures in close proximity to the track, thus it will be seen that a very efficient means has been provided for causing the figures to clear the hurdle and return to engagement with the track.

The figures for convenience of illustration are shown in the form of horses having slots 22 to receive the cranks 16 between the spacing collars 18, and the legs of the horses touch the surface of the track lightly when the cranks reach their lowermost position so that the horses will be given a galloping effect, and due to the arrangement of the cranks, the horses of each pair will move relative to each other in a forward and rearward motion to give the effect of one horse gaining on the other. By having the slots 22 in the figures or horses they will maintain a perpendicular position when clearing the hurdle as shown in Figure 2 as well as retaining the stated position during their travel about that portion of the track not obstructed by the hurdle.

The spring motor 10 may be wound by a key 23 projecting upwardly through the top face of the base.

As shown in Figure 8, the figure or horse has an opening in that portion illustrating the jockey to receive the crank of the shaft and is provided with a slot 24 through which a clip 25 is passed and the latter is of V-shape having openings 26 in the ends thereof to receive the crank. The figures are so mounted on the cranks that the clips keep the figures properly positioned and prevent them from

having undue side motion and becoming tangled with each other.

While I have shown and described the preferred embodiment of my invention, it will be understood that minor changes in construction, combination and arrangement of parts may be made without departing from the spirit and scope of my invention, as claimed.

Having thus described my invention, what I claim is:

1. A toy comprising a circular track, a hurdle on said track, a post located centrally of said track, a segmental gear carried by said post, combined supporting and propelling means journalled on the post, a shaft 80 journalled to said means, a gear secured to said shaft and engaging the segmental gear to rotate the shaft during the rotation of said combined supporting and propelling means, means for rotating said last named means, 85 cranks on said shaft, and figures carried by the cranks.

2. A toy comprising a circular track, a hurdle on said track, a post located centrally of said track, a segmental gear carried by said post, combined supporting and propelling means journalled on the post, a shaft journalled to said means, a gear secured to said shaft and engaging the segmental gear to rotate the shaft during the rotation of said 90 combined supporting and propelling means, means for rotating said last named means, cranks on said shaft, and figures pivotally secured to the cranks.

3. A toy comprising a circular track, a hurdle on said track, a post located centrally of said track, a segmental gear carried by said post, combined supporting and propelling means journalled on the post, a shaft journalled to said means, a gear secured to 100 said shaft and engaging the segmental gear to rotate the shaft during the rotation of said combined supporting and propelling means, means for rotating said last named means, 105 cranks on said shaft, figures pivotally secured to the cranks, and spacing collars on the cranks located at opposite sides of the figures to prevent said figures from becoming tangled.

4. A toy comprising a circular track, a hurdle on said track, a post located centrally of said track, a segmental gear secured to the post, a sleeve journalled on the post, a supporting arm carried by the sleeve, journals pivoted to the arm, a shaft rotatably mounted 115 in the journals, a gear secured to said shaft and engaging the segmental gear, tension means for urging the inner end of the shaft downwardly to cause the gear of said shaft to move in a plane below the segmental gear 120 when disengaged therefrom, cranks formed on the outer end of the shaft, figures journalled to said cranks, means for rotating the sleeve, and an inclined flange formed on the segmental gear to be engaged by the gear 125 130.

of the shaft when the last named gear has moved in a plane below the segmental gear.

5. A toy comprising a hollow base having its upper face of circular form to provide an annular track, a post carried by the base, a segmental gear secured to the post, a sleeve journalled on the post, arm carried by said sleeve, bearing pivoted to said arm, a shaft journalled in said bearings, a gear secured to 10 said shaft and engaging the segmental gear and adapted to move off said gear during the rotation of the sleeve, tension means for urging the inner end of the shaft downwardly, cranks formed on the outer end of the shaft, 15 figures journalled to said cranks, a downwardly inclined flange formed on the segmental gear for elevating the outer end of the shaft when the gear of said shaft becomes disengaged from the segmental gear, and a 20 spring motor carried by the base for rotating the sleeve.

6. A toy comprising a circular track, a hurdle on said track, a post located centrally of said track, a segmental gear secured to the 25 post, a sleeve journalled on the post, an arm carried by said sleeve, a bearing pivoted to the arm, a shaft journalled in said bearings, a gear secured to the shaft to engage and disengage the segmental gear during the rotation of the sleeve, cranks formed on the outer end of the shaft, tension means between the 30 arm and bearings for urging the inner end of the shaft downwardly, figures journalled on the cranks and having slots, clips extending through the slots and journalled to the 35 cranks, and means for rotating the sleeve.

In testimony whereof I affix my signature.
WILLIAM O. ROEDER.
